UNITED STATES PATENT OFFICE

2,170,430

SMOKING PIPE

Milton Schnaier, New York, N. Y.

Application February 18, 1937, Serial No. 126,314

5 Claims. (Cl. 131—215)

My invention relates to improvements in smoking pipes, and the same has for its object to provide a pipe which is simple in construction and efficient in operation.

5 Further, said invention has for its object to provide a pipe in which the oils or distillates released or produced in the course of smoking are abstracted or removed from the smoke before the smoke reaches the mouth piece of the pipe.

10 Further, said invention has for its object to provide a pipe which includes a fluid absorbing element or cartridge capable of being readily removed, replaced or renewed.

Further, said invention has for its object to 15 provide a pipe in which the smoke conducting passage or duct thereof includes a portion readily accessible from the outside of the pipe for receiving the absorbent element or cartridge.

Further, said invention has for its object to 20 provide a pipe which is capable of use, as desired, either with or without the absorbent element or elements in place therein.

Further, said invention has for its object to provide a pipe in which the smoke conducting 25 passage or duct includes a plurality or succession of cartridge-containing chambers for effectively absorbing the liquid constituents of the smoke or distillates resulting from the combustion of the tobacco.

30 Further, said invention has for its object to provide a pipe in which the absorbent-receiving portion of the smoke conducting passage is disposed in the bowl wall in angular relation to the longitudinal run of the smoke conducting passage.

Further, said invention has for its object to 35 provide a pipe in which the absorbent-receiving portion of the smoke conducting conduit may be readily opened at the outer end thereof to permit access thereto and closed to establish communication through the smoke conducting passage from the bowl of the pipe.

Further, said invention has for its object to 40 provide a pipe in which the closure for the absorbent-receiving chambers includes a tubular elbow or bridging member engageable with the open ends of said chambers to establish communication therebetween, and which is readily disengageable to allow access thereto.

45 Further, said invention has for its object to provide a pipe in which the closure for the absorbent-receiving means is yieldingly retained in closed position for maintaining the smoke conducting passage effectively sealed at the entrance 50 to the absorbent-receiving portion thereof.

Other objects will in part be obvious, and in part be pointed out hereinafter.

To the attainment of the aforesaid objects and ends my invention consists in the novel features of construction, and in the combination, connection and arrangement of parts hereinafter more fully described and then pointed out in the claims.

In the accompanying drawing—

Figure 1 is a side elevation of one form of pipe constructed according to and embodying my said 10 invention;

Fig. 2 is a longitudinal section thereof;

Fig. 3 is a plan thereof;

Fig. 4 is an enlarged section thereof on the line 15 4—4 of Fig. 3;

Fig. 5 is a similar section showing a modified construction feature, and

Fig. 6 is a longitudinal section illustrating a modified form of the invention.

In said drawing 10 designates the bowl of the pipe which is substantially cylindrical in outline and has a rounded base 11. The bowl is provided with a central opening 12 having a shoulder 13 near its lower end upon which is supported a perforated bottom plate or partition 14 forming a 25 smoke chamber 15 at the bottom of the bowl 10. The smoke chamber 15 improves the combustion and prevents the formation of gummy deposits within the pipe.

The bowl 10 has its wall at the rear enlarged or thickened to provide an extension 16 having therein cylindrical chambers 17 and 18 extending vertically therethrough in heat conductive relation to the interior of the bowl 10, and forming an absorbent-receiving means having open upper 30 ends 19 accessible at the top of the extension 16.

The chambers 17 and 18 constitute ascending and descending portions of the smoke conducting passage or duct 20, and are disposed transversely or angularly relative to the longitudinal run 20^a 40 of the passage 20 formed in the stem 21. The bore 20^a at the outer end of the stem 21 is enlarged to form a socket 22 into which is fitted the reduced end 23 of the mouth piece or bit 24. The chamber 17 communicates at the lower end thereof with the outlet 25 leading from the smoke chamber 15, and the chamber 18 communicates at the lower end 26 thereof with the duct or bore 20^a. The outlet 25 and the bore 20^a are separated from each other by the intervening wall or partition 27 to prevent direct communication therebetween.

Cylindrical filter or absorbing elements or cartridges 28, preferably made of compressible absorbent cotton or other suitable material, are dis- 55

posed within the chambers 17 and 18 in position to substantially fill the same. Preferably, the chambers are formed with beads or ledges 29 substantially at the junctures thereof with the longitudinal run of the smoke duct to form seats for the cartridges and to retain the same within the chambers 17 and 18 above the longitudinal run 20^a of the smoke passage and the outlet 25.

Means 30 are provided for normally closing the open ends 19 of the filter chambers 17 and 18 and establishing, as a result of the closure of said open ends 19, which constitutes a vent into the smoke passage, communication between said chambers and through the smoke conducting passage 20 as a whole. Said means 30, as one example, comprises a tubular bridging member or yoke 31 having angularly directed tapering open ends 32 fitting into the tapering openings 19. The member 31 is preferably carried by stem 20 or member 33 slidably in a plate or abutment 34 secured within the enlarged end portion 35 of the recess 36 provided in the extension 16 between the chambers 17 and 18. The lower, round portion of the stem 33, within the recess 36 and below the plate 34 carries a coil spring 37 retained therein by the abutment 38, and normally serves to retain the member 31 retracted and in position engaging said openings 19. Preferably the upper end 33^a of the stem 33 is made polygonal in cross section to prevent rotation thereof within the plate 34 and to insure the member 31 being aligned with the openings 19 to properly engage therewith when the member 31 is released and permitted to return to normal position. If so desired, as shown in Fig. 5, the member 31, in the released or engaged position, may be housed within a suitable recess 39 formed in the top of the extension wall 16 to prevent undue projection of said member 31 above the top of the pipe.

As shown in Fig. 6, the ascending and descending portions 17 and 18 of the smoke conducting passage 20 constituting the absorbent receiving chambers may be communicatively connected contiguous to the open ends 19 thereof by a transverse or connecting passage portion 40 formed in the extension 16 itself. The open ends 19 may then be closed by a member in the form of a plate or disk 41 preferably seated within a recess 42 formed in the top of the extension 16. The plate or disk 41 is yieldingly retained seated by the spring mounting 43 like that described above and more fully illustrated in Figs. 1 to 4. The disk 41 is preferably provided with a finger piece 31^a for enabling the same to be lifted in order to insert or remove the absorbent elements 28 into or from the chambers 17 and 18. The plate or disk 41, like the member 30, serves to close or seal the entrance 19 to the cartridge-receiving chambers. By sealing this vent 19 into the smoke conducting passage 20, communication is established therethrough, rendering the passage operative for smoking.

In operation, the member 31 or 41 may be readily grasped by the finger piece 31^a and raised against the tension of the spring 37 to clear the openings 19 and allow the insertion or removal of the filtering cartridges 28 into or from the chambers 17 and 18. When the member 31 or 41 is released, it closes or seals the openings 19 to establish communication through the passage 20 from the bowl 10 to the discharge end of the pipe. The smoke in being drawn through the pipe traverses the succession of filtering or absorbent elements 28 which remove the distillates, oils and

other liquids from the smoke, thereby freeing the smoke from undesirable constituents for delivery in a dry, clean state to the mouth. The heat-conducting relation of chambers 17 and 18 to the bowl 10 causes the moisture absorbed by the elements 28 to be rapidly evaporated which prevents the filtering or absorbing material from becoming excessively wet or soggy.

The provision of the partition or plate 14 and the smoke chamber 15 prevents the blocking up or clogging of the entrance 25 to the filter chamber 17 by the tobacco packed into the bowl 10, and the contamination of the absorbent material by the tobacco or by the ash resulting from the combustion.

In my invention the cartridges 28 may be readily inserted into and removed from the offset chambers 17 and 18 by a simple operation, rendering it unnecessary to remove the bit 24 as in types of pipes having a filter in the longitudinal run of the smoke duct or bore. The pipe is also fully operative for smoking when the absorbent elements 28 are removed.

By my invention I am enabled to obtain a substantially dry smoke without impairing the normal operation of the pipe or unduly complicating the structure thereof. By the provision of the plurality of cartridge receiving chambers formed in the wall of the bowl as described, the absorbent path is substantially extended or lengthened without unduly increasing the size of the pipe.

Having thus described my said invention what I claim and desire to secure by Letters Patent is:

1. A smoking pipe comprising a bowl, a stem portion extending therefrom, the wall of said bowl and said stem portion having a smoke conducting passage therein including ascending and descending portions in said wall open at the outer ends thereof, a tubular bridging member engageable with the open ends of said ascending and descending portions for establishing communication therebetween, and resilient means disposed within said wall and connected to said bridging member for retaining the same in engaged position.

2. A smoking pipe comprising a bowl, a stem portion extending from the bowl, said parts having a smoke conducting passage therein including relatively enlarged ascending and descending substantially vertical portions formed in the wall of said bowl in spaced apart relation and open at the outer ends thereof, said wall between said ascending and descending portions having a recess therein, absorbent elements disposed in said ascending and descending portions, closing means for establishing free communication between said ascending and descending portions beyond the outer ends of said absorbent elements, and resilient means disposed in said recess and connected to said closing means for yieldingly retaining the same in closed position.

3. A smoking pipe comprising a bowl, a stem extending therefrom, said parts having a smoke conducting passage therein including relatively enlarged ascending and descending portions formed in the wall of said bowl in spaced apart relation and having openings at the outer ends thereof substantially in the same plane, said wall between said ascending and descending portions having a recess therein, absorbent elements disposed in said ascending and descending portions, a tubular bridging member engageable with said open ends for establishing communication between said ascending and descending portions,

and resilient means disposed in said recess and connected to said bridging member for retaining the same in engaged position.

4. A smoking pipe comprising a bowl, a stem portion extending from said bowl, said parts having a smoke conducting passage therein including relatively enlarged ascending and descending portions formed in the wall of said bowl in spaced apart relation and having openings at the edge of said wall, said wall having a recess formed therein between said ascending and descending portions substantially in alignment therewith, closing means for said ascending and descending portions at the open ends thereof and serving to establish communication therebetween, and means within said recess connected to said closing means at an intermediate point thereof for yieldingly retaining said closing means in closed

position, said last named means being mounted to allow rotation of said closing means, when the same is lifted, to a position at right angles to the closing position.

5. A smoking pipe comprising a bowl, a stem portion extending therefrom, the wall of said bowl and said stem portion having a smoke conducting passage therein including ascending and descending portions in said wall open at the outer ends thereof for receiving absorbent elements, a member serving to cover the open ends of said ascending and descending portions and establish free communication therebetween, and resilient means disposed within said wall and connected to said member for retaining the same in engagement with said wall.

MILTON SCHNAIER.
